(57) **CLAIM**

The ornamental design for a battery unit case for vibration sensor as shown and described.

DESCRIPTION

FIG. 1 is a front and left perspective view of a battery unit case for vibration sensor, showing our new design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof.

FIG. 8 is a cross-sectional view taken along the line 8-8 in FIG. 4.

FIG. 9 is a cross-sectional view taken along the line 9-9 in FIG. 2; and,

FIG. 10 is a cross-sectional view taken along the line 10-10 in FIG. 2.

The broken lines illustrate portions of the battery unit case for vibration sensor that form no part of the claimed design.
